US00D859486S

(12) **United States Design Patent** (10) Patent No.: **US D859,486 S**
Cramb et al. (45) Date of Patent: **** Sep. 10, 2019**

(54) **CONFOCAL MICROSCOPE**

(71) Applicant: **CALIBER IMAGING & DIAGNOSTICS, INC.**, Rochester, NY (US)

(72) Inventors: **Allison L. Cramb**, Rochester, NY (US); **Christopher C. Distasio**, Rochester, NY (US); **William J. Fox**, Rochester, NY (US); **Benny Alexander**, Lakeway, TX (US); **Steven Ridge**, Glen Ellyn, IL (US); **Anthony J. Roberto**, Henrico, VA (US); **Tyler W. Porter**, Honeoye Falls, NY (US)

(73) Assignee: **CALIBER IMAGING & DIAGNOSTICS, INC.**, Rochester, NY (US)

(**) Term: **15 Years**

(21) Appl. No.: **29/540,725**

(22) Filed: **Sep. 27, 2015**

(51) LOC (12) Cl. **16-06**

(52) U.S. Cl.

USPC **D16/131**

(57) **CLAIM**

The ornamental design for a confocal microscope, as shown and described.

DESCRIPTION

FIG. 1 is a perspective view looking downwardly at the left side of a confocal microscope in accordance with our design;

FIG. 2 is a left side view thereof;

FIG. 3 is a right side view thereof;

FIG. 4 is a front elevation view thereof;

FIG. 5 is a rear elevation view thereof;

FIG. 6 is a top view thereof;

FIG. 7 is a bottom view thereof;

FIG. 8 is a perspective view looking at the right side thereof in which the imaging head of the confocal microscope is shown tilted from its position shown in FIGS. 1-6; and, FIG. 9 is a perspective view looking at the rear elevation thereof in which the imaging head of the confocal microscope is also shown tilted from its position shown in FIGS. 1-6.

1 Claim, 9 Drawing Sheets
